UNITED STATES PATENT OFFICE

171,562

WRISTBAND FOR A WRIST WATCH

Elmer J. Towle, San Francisco, Calif.

Application October 10, 1952, Serial No. 21,779

Term of patent 14 years

(Cl. D45—4)

To all whom it may concern:

Be it known that I, Elmer J. Towle, a citizen of the United States, residing at San Francisco, State of California, have invented a new, original, and ornamental Design for a Wristband for a Wrist Watch, of which the following is a specification, reference being had to the accompanying drawing, forming part thereof.

Figure 1 is a front elevational view of a wristband for a wrist watch showing my new design; and

Figure 2 is a side elevational view thereof.

I claim:

The ornamental design for a wristband for a wrist watch, as shown.

ELMER J. TOWLE.
